BEAM DOFFING MECHANISM

Thomas F. Suggs, Gastonia, N. C., assignor to
Cocker Machine and Foundry Company, Gas-
tonia, N. C., a corporation of North Carolina

Application November 13, 1946, Serial No. 709,638

6 Claims. (Cl. 28—32)

1

This invention has general reference to warping machines and, more particularly, relates to the species or form thereof generally known as section-beam warpers including means for rotatively sustaining a beam on which the yarns are wound.

The primary object of this invention is to provide a novel form of motorized doffing device for association in beam warpers of the above noted species, whereby the beam when filled with yarn is lowered for removal, and re-elevated after replacement by an empty beam.

Another object is to provide an electrical-system including movement controlling and limiting switches whereby operation of the warping machine, when the beam is in doffing position, cannot take place.

While the foregoing objects are indicative in a general way of the fundamental aims of this invention, other objects with ancillary advantages will be evident to those skilled in the art, upon a full understanding of the construction, combination and arrangement of the means hereinafter disclosed; but it will also be appreciated that the invention is susceptible of other embodiment, or modified form, than that typically illustrated by the accompanying sheets of drawings, and more particularly defined in the concluding claims.

In the drawings:

Fig. 1 is a side elevation of a sectional beam warping machine embodying the mechanical improvements in accordance with this invention; and,

Figs. 2-7 inclusive are consecutive wiring diagrams of the electrically-controlled means whereby the machine of Fig. 1 may be operated, and each of which diagrams is hereinafter fully explained.

In describing the form of this invention exemplified by the drawings herewith, specific terms will be employed for the sake of clarity, but it is to be understood the scope of said invention is not thereby limited; each such term being intended to embrace all reasonable equivalents which perform the same function for an analogous purpose.

Referring more in detail to the drawings and first to Fig. 1 the reference character 10 comprehensively designates a sectional beam, the spindle or shaft 11 whereof is removably journaled in suitable bearings 12; which in turn are carried by spaced arms 13, one only being visible in the drawing; while said arms 13 are respectively fulcrumed at 14 to the correspondingly spaced side frames 15 of the warping machine.

2

Normally the beam supporting arms 13 occupy the vertical position shown in full lines or with the beam 10 elevated relative to floor level 16 and in which position said arms are retained by means of clamp-yokes 17, pivoted at 18, to the respectively associated side frame 15, so as to be pivotal downward or horizontal as shown, or swingable vertically upward to the dot-and-dash line position, over reduced projections 19 integral with, or at the free ends of, the arms 13 aforesaid. Each yoke 17 is fitted with a clamp-screw 20 operable by a hand-wheel 21, or the like, and whereby the respective arms 13 are firmly secured in abutment against the confronting side edges of the frames 15, in an obvious manner.

For the purpose of lowering the arms 13 to "doff" after the sectional beam 10 has been fully wound with yarn, and to subsequently re-elevate the same into normal or upright position after mounting a fresh beam 10 for winding, I preferably utilize the mechanism now to be described. This mechanism includes a pair of spaced sprocket-wheels 22, one only being visible in the drawing, which are conveniently secured by means 23 to a shaft 24 extending transversely intermediate and journaled in the side-frames 15 of the machine. Each such sprocket-wheel 22 has appropriately attached thereto at 25, for instance, one end of a cooperative link-chain 26 which, in turn is trained over an idler 27, rotatively supported by suitable means 28 in the upper part of the adjoining side frame 15; whereas the other end of said chain 26 is connected at 29 to an associated screw-bolt 30, adjustable 31 in the outer end of the planarly-related arm 13; all as well understood by those conversant with the art.

Appropriately made fast to the outer end of the shaft 24, at one side of the machine, as by a key 31, is a worm-gear 32 in mesh with the worm-drive 33 of a transmission-shaft 34, journaled in spaced bearings 35, said shaft being operatively coordinated by a worm-gear combination or couple 36 to the power shaft 37 of a reversible electric motor 38.

Stopping of the motor 38 at the proper times upon movement of the arms 13 downward for "doffing," and on upward return thereof to normal or the active position for re-beaming with warps is automatically effected, in accordance with this invention through the medium of lower and upper limit-switches 39, 40, respectively, which as later on explained effect closure of electric circuits through the motor 38. As shown, the plunger 41 of the limit-switch 39 is arranged

to be moved by the head 42 of an adjustable screw-bolt 43 carried by a laterally projecting bracket or lug 44 on, or secured to, the heel-portion 45 of the arm 13, adjacent its fulcrum 14; whereas the plunger 46 of the limit switch 40 is engageable by a projection or pad 47 near the outer or upper end of said arm 13. Starting of the motor 38 is effected, as hereinafter further amplified, by means of a safety-control or reversing-switch 48 at the top of one of the side frames 13, for example only, and said switch being conveniently equipped with "raising and lowering" push-buttons 49, 50 respectively.

Referring now, more particularly, to Figs. 2-6 inclusive which show how the improved doffing mechanism of this invention is electrically controlled and activated, it is first to be noted that the safety-control or reversing-switch 48, as well as the associated limit-switches 39, 40 are supplied with current by lines 51, 52 from a single-phase or 110-v. source of electric current, not shown; whereas the reversible-motor 38, with its single magnetic-switch 53 and duplex-switches 54, 55, respectively, are served with current by lines 56, 57, 58 and lines 56', 57', and 58', from a multi-phase source of electric current, as readily understandable by those conversant with the art. It is also to be further noted that the beam supporting-arm or arms 13 are normally in the up, or neutral, position with no electric current influencing any one of the switches 48, 40, and 39, or the magnetic-switches 53, 54 and 55.

Still referring to Fig. 2 it is to be borne in mind that a primary circuit $p-c$ is closed, as herein-after indicated, through the main drive of the warper to rotate the sectional-beam 10, such drive not being shown as it forms no part of the present invention. This main drive or primary circuit $p-c$ is conveniently set-up when the electric current is switched "on," incidental to the limit-switch 40 being held closed by the arm 13, under retainer-action of the clamp-yoke 17, whereby a flow of current from the multi-phase source may be by way of the line 56 across the contacts 59 of said limit switch, to the coil 60 of magnetic-switch 53 whereby the associated core 61 is held to the contacts 62 and therefrom through line 58, as indicated by the associated arrows.

Assuming now that the sectional beam 10 be full of yarn, ready for "doffing," the operator first breaks the primary circuit $p-c$ above explained, then releases and swings the clamp-yokes 17 up or into the dot-and-dash line position of Fig. 1, whereupon the down-button 50 is depressed to initiate the doffing operation. Such depression of the button 50, into the position of Fig. 3, closes or completes a second circuit $s-c$ from the 110-v. source of electric current through the feed line 51—in the direction of the associated arrows—to the lower contact 63 across the reversing-switch 48 to the contacts 64, through the line 65 and across limit-switch 39, which is still closed, to the coil 66 of the duplex magnetic-switch 55, thereby energizing said coil to move the right-hand core 67 thereof from the neutral position of Fig. 2 into engagement with the lower contacts 68, while the left-hand core of said switch is mechanically and simultaneously elevated by an oscillatable or rockable coupler 67' into engagement with contacts 68', for reasons hereinafter explained. It is also to be noted that completion of the second circuit $s-c$, above referred to, is from the coil 66 by way of a line 69, across the contacts 70 of the magnetic-switch 53 to line 52. It will, of course, now be readily apparent that interruption of the 75

primary or warper main-drive circuit $p-c$ de-energizes the coil 60 of the magnetic-switch 53 whereby the core 61 thereof automatically assumes the position shown in Fig. 3. At the same time it will be evident that incidental to bridging of the contacts 68, 68' of the switches 54, 55 by the associated cores 67, 67', a flow of current from the multiphase source closes, a circuit $r-m-c$ through the reversible electric motor 38 as follows, for instance, by way of the line 58' branch 71 across contacts 68 and line 72 to motor 38 with rotation of the power-shaft 37 of the latter in a clockwise direction, as indicated by the curved arrow thereon, and return by way of branch 73 to line 56'; at the same time a corresponding flow of current in the same direction to the motor 38 takes place from line 57' by way of branch 74, across contacts 68' and line 75 through motor 38 to branch 73 and line 56'. As a result of thus energizing the motor 38 it will be understood that the worm-gear couple 36 and transmission-shaft 34 will rotate clockwise, and that, through the worm-driver 33 and meshing gear 32 the transverse-shaft 24 will correspondingly rotate; whereby the respective link-chains 26 are gradually released and, due to the relatively outward vertical location of the axis of the sectional-beam 10 relative to that of the fulcrum or pivotal axis 14 of the spaced arms 13, said beam will commence to angularly recede from engagement with the side frames 15, in accordance with known practice. It is to be particularly noted, at this juncture, that the movable component 46 of the limit switch 40 will automatically follow recession of the arms 13 into bridging engagement with the contacts 80, see Fig. 4, and, at the same time, effectively prevent re-starting of the warper means by positive breaking of the primary-circuit $p-c$ or flow of current across the contacts 59 during the doffing operation, while the secondary and reversible-motor circuits $s-c$ and $r-m-c$ continue closed until the head 42 of the adjuster-screw bolt 43 contacts the plunger 41 of the lower limit-switch 39, see Fig. 5. As the sectional beam 10 reaches floor-level 16 the plunger 41 of the limit switch 39 automatically shifts from the position of Fig. 4 to that of Fig. 5, whereby the aforementioned circuit $s-c$ is opened with resultant de-energization of the coil 66 and simultaneous assuming by the cores 61, 67', through aid of the coupler 67'', of the position also shown in Fig. 2, in conformity with known practice and automatic stoppage of the motor 38, by opening of the circuit 58', 71, 72, 73, 75 and 56' as readily understandable without further elaboration herein.

Assuming now that an empty sectional beam 10 has been placed across the spaced arms 13, the operator depresses the up-button 49, in Fig. 6, to again close the second $s-c$ circuit from the source of 110-v. current; when it will be seen that said circuit is completed from line 51 to lower contact 63 of switch 48, through loop 76, to and across the inner contacts 77 of said switch; thence to and across the outer contacts 78 of button 50 and line 79 to outer contacts 80 of limit-switch 40 and, via line 81, to the left-hand coil 66' of limit-switch 54, with retraction of the core 67' thereof; while said circuit is completed by way of line 69, across limit switch contacts 70 and line 52, as before set forth, and resultant rotation of the motor 38 in a counter-clockwise direction, as indicated by the curved arrow thereon. Upon completion of the $s-c$ circuit just explained with energization of the coil 66' and retraction of the

core 67' thereof it will be understood that the circuit $r-m-c$ to the motor 38 is as follows. Starting from line 58' current will flow via branch 71, lower contacts 82 of switch 54, and line 75 to motor 38, branch 73 and line 56'; as well as from line 57' via branch 74 to point 83 to and across upper contacts 84 to point 85, and line 72 to motor 38, and return branch 73 to line 56'.

Upon the motor 38 commencing to rotate counter-clockwise, with corresponding rotation of its power-shaft 37, and through consequential reverse rotation of the mechanisms 36, 34, 33, transverse shaft 24 and associated sprocket-wheels 22 will be similarly turned, whereby the link-chains 26 will be gradually wound onto the said sprocket wheels 22. Incidental to winding-up of the chains 26 the beam 10 will commence to angularly elevate on the fulcrum 14; while the plunger 41 of the limit switch 39 will follow such advancement until prevented from further coaction with the head 42 of the adjuster screw-bolt 43, and resultant abutment across the contacts 86 of the limit-switch 39, see Fig. 7; while the secondary and reversible-motor circuits $s-c$ and $r-m-c$ remain closed until the pad 41 on the arm 13 engages the associated plunger 46 of the limit-switch 40 and forces said plunger inward, from the position shown by Fig. 7 to that of Fig. 2. Now it will be apparent that movement of the plunger 46 away from the contacts 80 breaks the elevating circuit $s-c$, with consequent interruption of the circuit $r-m-c$ and stoppage of the motor 38, in view of deenergizing the coil 66', whereby the cores 67' and 67 automatically become restored to neutral position of Fig. 2, with all of the current-supply lines 51, 52; 56, 57, 58; and 56', 57', 58' "dead"; whereupon the operator re-locks the pivotal arms 13 in the full-line position of Fig. 1 by aid of the clamp-yokes 17, as well understood from the preceding description thereof, ready for the inception of filling the empty beam 10, in the manner aforesaid. Incidentally it is noticeable that the limit switch 40 is only open when the beam 10 is being doffed, and the arms 13 are down to 45 floor-level.

From the foregoing it is felt that the merits and advantages of the invention hereinbefore disclosed will be fully appreciated; and while there has been shown and described a preferred embodiment thereof the same is not to be considered conclusive, seeing that sundry changes and variations may be effected by those skilled in the art without departing from the spirit of said invention, or exceeding the scope of the following claims.

Having described my invention, I claim:

1. Beam doffing mechanism for a warping machine including fulcrumed normally vertical supports for rotatively sustaining a beam in elevated position outwardly relative to the fulcrum pivot point of said supports; a reversible power means; and means for selectively controlling starting of the power means to lower the supports for beam doffing, and to return the

same into vertical position after mounting an empty beam thereon.

2. Beam doffing mechanism for a warping machine or the like including spaced beam supporting arms fulcrumed at their lower ends to the machine side frames and normally occupying an upright position with the beam elevated for reception of yarn, said beam having its axis of rotation located outward relative to the fulcrum axis of the supporting arms; reversible power means, a winding means arranged to be driven by the power means; and spaced flexible elements extending from the winding means and connected to the upper part of said arms.

3. Beam doffing mechanism according to claim 2, further including releasable clamp means for engagement with the beam supporting arm upper ends to hold the latter normally in upright position.

4. Beam doffing mechanism according to claim 2 in which the winding means is driven by the power means through worming gearing.

5. Beam doffing mechanism for a warping machine or the like, including spaced supporting arms fulcrumed at their lower ends to the machine side frames and normally occupying an upright position in said machine with the beam elevated for reception of yarn, the axis of rotation of said beam being outwardly located relative to the fulcrum axis of the supporting arms; a reversible electric motor; a power circuit with interposed means for controlling the motor; and operating means between the motor and the beam with flexible connections to the spaced supporting arms.

6. Beam doffing mechanism according to claim 5, further including movement limiting switches in circuit with the motor and positioned respectively above and below the axis of the beam and the fulcrum axis of the supporting arms for actuation by said supporting arms to automatically stop the motor when the beam has been fully raised to active position in the machine, or lowered for the doffing of the beam.

THOMAS F. SUGGS.
